UNITED STATES PATENT OFFICE.

WILLIAM B. POTTER, OF SCHENECTADY, NEW YORK, ASSIGNOR TO THE GENERAL ELECTRIC COMPANY, A CORPORATION OF NEW YORK.

SURFACE-CONTACT RAILWAY SYSTEM.

SPECIFICATION forming part of Letters Patent No. 729,411, dated May 26, 1903.

Application filed February 11, 1899. Serial No. 705,235. (No model.)

To all whom it may concern:

Be it known that I, WILLIAM B. POTTER, a citizen of the United States, residing at Schenectady, county of Schenectady, State of New York, have invented certain new and useful Improvements in Surface-Contact Railway Systems, of which the following is a specification.

My present invention relates to surface-contact railway systems, or so-called "closed-conduit" systems, and aims to obviate a defect which may occur with many systems at present in use in which the so-called "leakage-current" may act to hold up one or more of the electromagnetic switches. In general these systems comprise a feeder, sectional conductors or contacts which may be contact studs or rails of considerable length, and electromagnetic switches of one form or another which are operated by certain circuits to connect the sectional conductors in sequence to the feeder as the car passes and to disconnect each conductor-section as soon as the collector is carried by the car to make contact with the next succeeding section. Usually two rows of studs or sectional conductors are employed, one of which, commonly called the "working" conductor, is connected to the feeder, and the other of which, called the "energizing-conductor," is connected to the coils of the electromagnetic switches, the coils being usually grounded. It is manifest that with this arrangement if there should be for any reason—as, for instance, by wet weather or by accidental connection being made between them—a leakage of current from the working conductor which has been connected to the feeder to the corresponding energizing-conductor operating its switch the latter would be held up and the working conductor would be maintained alive in the street. This has been a source of danger in some surface-contact systems, and several attempts have been made to overcome it, most of which are not altogether successful. I am aware of certain patents which disclose methods of short-circuiting the line, and thereby blowing a fuse at a leaking section, or of shunting the line-current at a leaking section to operate an auxiliary feeder-switch. These methods are laborious, costly, and impractical.

I aim by the present invention to eliminate this difficulty, which I do by providing upon the car a means of shunting to ground any leakage-current which might otherwise pass from the working conductor to the energizing-conductor. The means employed are such as to operate after the collector or contact-shoe which collects the motor-current (and which usually operates the pick-up switches) has left the working conductor.

Briefly described, one construction of apparatus embodying the invention is as follows: In addition to the ordinary motor-shoe or working collector, which also operates the pick-up switches, I provide other shoes, which are grounded, and so arrange these latter that they will make contact with all of the sections of energizing-conductors without touching any of the working conductors. As a convenient method of effecting this result I extend the sections of energizing-conductors so that the grounded auxiliary shoes may be out of line with the motor-shoe and still register with the energizing-conductor.

In the drawing attached to this specification, which represents in diagram one form which my invention may take, A is a generator, one pole of which is connected to the track-rail or ground D, while the other pole is connected to a feeder H. Located along the line of the road is a sectional conductor B, which may be of any preferred form, but is here shown as composed of a succession of studs supposed to project only a short distance above the surface of the earth. Each of these studs is connected to two magnetically-operated switches G, as shown, so that the closing of either switch will connect the stud with the feeder H. A shoe F travels upon the studs B and collects current for the motor or motors M. For example, in the position shown current flows from the feeder H to the switch G', to the working collector F, to the motor M, through the car-wheel I, to ground at D, and thence back to the generator A. I do not illustrate the controllers, &c., as they are now well-known in the art and form no part of my present invention.

The switches G are actuated by coils P, each of which is connected at one end to ground, as shown, or to the track-return and

at the other end to one of the studs C. In the position shown current flows from the shoe F to the stud C', through the coil P', and to ground. The coils P are so proportioned that the current is small in amount as compared with the current normally flowing to the motors.

The system as thus far explained will operate when once the switch G' is closed, as the shoe F will always as the car moves in either direction furnish current for picking up each switch G, controlling the stud B next in advance. Normally each switch G will open when the shoe F leaves the corresponding stud C; but it may happen, as has been stated above, that current will leak from the live stud B' to the stud C' after the shoe F has passed over them, and thus the switch G' might be held closed. To avoid this, I so shape each of the studs C that it makes contact not only with the shoe F, but also with the auxiliary shoes F' F'', which are connected direct to ground through the car-axle, as shown. Suppose that in the illustration the car is moving to the right. The shoe F is furnishing current to the car-motors from the working stud B' and forms with the energizing-stud C' a shunt to ground through the switch-coil P'. The shoe F has just left the next rear energizing-stud with which the grounded shoe F' is about to engage. When this engagement takes place, any leakage-currents, even those which may be passing from the working stud through the coil of the switch which is connected to the next rear energizing-stud, will be shunted by the shoe F' through the car-axle to the track-return and the switch will open. The shoe F' continues thus to short-circuit the switch-coil to earth until the shoe F has been carried beyond the energizing-stud C' and has left the switch G' open and the working stud B' de-energized. However, if leakage-currents should keep the switch G' closed the working stud B' would remain alive and leakage-currents might flow therefrom after the shoe F' had left the next rear energizing-stud and pass through the switch-coil to close the switch and leave the rear energizing-stud alive. To prevent this occurrence, the shoe F' is of sufficient length to bridge the two successive energizing-studs between which the stud B' is located, and thus the leakage-currents are shunted from the stud C' to ground, and it is impossible for the stud B' to remain energized after the shoe F' has cleared the energizing-stud behind B'.

In order to insure the above-described operation when the car is moving in either direction, the energizing-studs C C', &c., extend or are offset laterally in both directions from the line of the working studs B B', &c.

For the purpose of picking up the switches when the car has lost its current I may provide a storage battery SB, carried on the car. One end of this battery is connected to ground and one end to the shoe F through a switch S.

It will be evident that by merely closing this switch for an instant it will be possible to pick up the switch G and start the system in operation. To avoid the necessity of carrying a storage battery on each car, I may provide contacts L', located, for example, in lamp-posts L at numerous points along the track or on another car. One or more contacts K K on each car will be connected to the shoe F either with or without the interposition of the switch S. If now the contacts L' and K be connected together, as by the flexible conductor N, current sufficient to pick up the switch G' will be at once available.

So far as I am aware I am the first in the art to provide means carried upon the car for preventing the electromagnetic switches of a surface-contact railway system from being held up by leakage-current without rendering any portion of the system inoperative or without the provision of extra apparatus and the first to carry an independent shunt-circuit for leakage-currents alone upon a car in such a system.

Having thus described my invention, what I claim as new, and desire to secure by Letters Patent of the United States, is—

1. In a surface-contact system, the combination of a source of current, sectional conductors, and electromagnetic switches for connecting the conductors in sequence to the source of current as a vehicle passes over the road, with means carried by the car for shunting leakage-currents from the sectional conductors directly through the car to ground.

2. In a surface-contact system, the combination of a feeder, sectional conductors, and electromagnetic switches for connecting and disconnecting the feeder and the conductors in sequence, with a short circuit direct to ground for leakage-currents, carried upon the car.

3. The combination in a surface-contact system, with a feeder, buttons connected to the feeder, an electromagnetic switch the coils of which are connected to pick-up buttons or studs in the roadway and which are operated in sequence to connect the first-named buttons with the feeder, of a circuit direct to ground carried upon the car and touching the pick-up buttons or studs only.

4. The combination with a feeder, studs connected to the feeder in sequence by electromagnetic switches the coils of which are in circuit with pick-up studs, of a shoe carried by the car and connected direct to ground, the shoe registering with the pick-up studs only.

5. In a surface-contact system, the combination of two rows of studs, a feeder, and electromagnetic switches, one of the rows of studs being connected directly to the feeder by the action of the switches, and the other row of studs being grounded through pick-up coils, the latter row of studs being of greater width than the former so as to project beyond them upon either side of a central line,

with a shoe making contact with both rows of studs supplying current to the motor and actuating the switches as it touches the studs in sequence, and grounded shoes in front and rear of the first, but out of line with it, so as to touch only one set of studs, whereby the car acts to short-circuit to ground any leakage reaching the pick-up studs and to prevent the switches being held up by leakage-currents.

6. In an electric-railway system, the combination with the feeder, of a sectional working conductor normally disconnected therefrom, an electromagnetic switch between each conductor-section and the feeder, a sectional switch-energizing conductor independent of said working conductor, and means for shunting leakage-currents from the energizing-conductors to ground.

7. In an electric-railway system, the combination with the feeder, of a sectional working conductor normally disconnected therefrom, an electromagnetic switch between each conductor-section and the feeder, a sectional switch-energizing conductor independent of said working conductor, a car, and means for shunting leakage-currents from the energizing-conductor through the car to ground.

8. In an electric-railway system, the combination with the feeder, of a sectional working conductor, an electromagnetic switch between each conductor-section and the feeder, a sectional switch-energizing conductor independent of said working conductor, a car, a working collector carried by the car which engages with the energizing-conductor sections and collects working current from the working conductor, and means for simultaneously therewith shunting leakage-currents to ground from the energizing-conductor section which the working collector has just left.

9. In an electric-railway system, the combination with the feeder, of a sectional working conductor, an electromagnetic switch between each conductor-section and the feeder and having its coil connected to ground, a sectional switch-energizing conductor, each section of which is connected with the coil of one of said switches, and means for shunting leakage-currents from the energizing-conductor to ground.

10. In an electric-railway system, the combination with the feeder, of a sectional working conductor, an electromagnetic switch between each section and the feeder, a sectional switch-energizing conductor, an electric-motor car, a collector carried by the car, connected with the motors, and engaging with the working and energizing conductors, and a grounded collector carried by the car which engages only with the energizing-conductor.

11. In an electric-railway system, the combination with a sectional working conductor, of a sectional energizing-conductor, a working collector carried by the car, and an auxiliary collector carried by the car, connected

with the track, and engaging only with the energizing-conductor.

12. In an electric-railway system, the combination with the feeder, of a sectional working conductor, an electromagnetic switch between each conductor-section and the feeder, a sectional energizing-conductor, each section of which is offset from the working conductor, a working collector carried by the car and engaging with both conductors; and a grounded collector carried by the car and engaging with the offset portions of the energizing-conductor.

13. In an electric-railway system, the combination with the feeder, of a sectional working conductor, an electromagnetic switch between each conductor-section and the feeder, a sectional energizing-conductor, each section of which extends laterally in both directions from the line of the working conductor, a working collector carried by the car and engaging with both conductors, and a grounded collector carried by the car and engaging with the lateral extensions of the energizing-conductor.

14. In an electric-railway system, the combination with the feeder, of a sectional working conductor, an electromagnetic switch between each conductor-section and the feeder, a sectional switch-energizing conductor, a working collector carried by the car, and a grounded collector carried by the car, of sufficient length to bridge two successive sections of the energizing-conductor, whereby leakage-currents are shunted to ground from the successive sections of the energizing-conductor.

15. In an electric-railway system, the combination with the feeder, of a sectional working conductor, an electromagnetic switch between each conductor-section and the feeder and having its coil connected to ground, a sectional switch-energizing conductor, to each section of which is connected the coil of one of said switches, a traveling collector for shunting a portion of the working current from a section of the working conductor to a section of the energizing-conductor and through the switch-coil to close the switch and energize the next section of working conductor, and an auxiliary traveling collector for short-circuiting each switch-coil to ground by shunting leakage-currents from the corresponding section of energizing-conductor.

16. In an electric-railway system, the combination with the feeder, of a sectional working conductor, two electromagnetic switches between each conductor-section and the feeder and having their coils grounded, a sectional energizing-conductor, each section of which is connected to one of the switch-coils, a traveling motor-current collector which engages with both sectional conductors, and a traveling grounded collector which engages only with the energizing-conductor.

17. In an electric-railway system, the com-

bination with the feeder, of a sectional working conductor, electromagnetic switches between the conductor and the feeder, a sectional energizing-conductor independent of
5 said working conductor, means carried by the car for energizing the switches and conducting current to the car-motors, and a traveling grounded collector which engages only

with the energizing-conductor to short-circuit the coils of the switches to ground. 10

In witness whereof I have hereunto set my hand this 9th day of February, 1899.

WILLIAM B. POTTER.
